(57) **CLAIM**

The ornamental design for a towel bar, as shown and described.

DESCRIPTION

FIG. 1 is a front perspective view of a towel bar of indeterminate length;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The towel bar is shown with a symbolic break in its length. The appearance of any portion of the article between the break lines forms no part of the claimed design. The dashed lines in FIGS. 2 and 4 do not form part of the claimed design. Shading is used in the drawings to better illustrate the design.
